A CORPORATION OF POLAND

PROCESS FOR PREPARING VALUABLE COMPOUNDS FROM THE REFINING WASTES OF
CRACKED PRODUCTS, PARTICULARLY CRACKED BENZINES

No Drawing. Application filed October 29, 1928, Serial No. 315,911, and in Poland September 24, 1927.

This invention relates to a process for obtaining, from the acids and lyes obtained as waste products in the refining processes of cracked products, particularly cracked benzines, various valuable compounds, some of which are related to the higher alcohols, whilst the remainder mainly consist of unsaturated compounds, which can be employed for various useful purposes.

10. When, for example, cracked benzines, obtained by any of the known methods, are subjected to the usual refining process with sulphuric acid, waste acids are obtained, which differ considerably from those which
15. are obtained during the refining of uncracked mineral oils and from which the above mentioned compounds may be isolated.

According to the invention the process consists in diluting the waste acids with water or slightly alkaline liquids. A supernatant oily layer and a lower aqueous layer are formed thereby. The oily layer contains the compounds of olefine character, whilst the main portion of the alcohols are to be found in the aqueous layer. The alcohol residues, which remain in the oily layer are removed therefrom by washing with water and the washings added to the first aqueous layer. The latter is then neutralized and subjected
20. to steam distillation whereby a water-alcohol mixture comes over, which is fractionated and distilled in known manner to effect a further separation of the constituents. The alcohols obtained in this way may be employed for denaturing and other purposes, for which higher alcohols are used.

The washed oily layer is also neutralized, again washed and then distilled with steam. The residue left in the still is separately further worked up. The distillate consists of a mixture of unsaturated compounds, which can be converted in known manner by condensation into compounds of higher molecular weight or transformed with siccatives into easily drying oils of a rubber-like character. Both the distillation and residual products are particularly adapted to be employed in the manufacture of lacquer and varnish.

50. The following example illustrates how the

process of this invention can be carried into effect:—

The benzine obtained for example, in a "Cross plant" is refined with 3% of about 88% sulphuric acid at 15° C. and acid tar, 55 which separates out, collected in a container. As compared with the acid tar from benzine and petroleum, which are obtained from uncracked mineral oil, the acid tar from cracked benzine is very mobile. On diluting, about 60 30% of a mobile oil of sp. gr. 0.830-0.860 separates out as an upper layer from the aqueous liquid underneath.

The acid-refined benzine is next washed with caustic lye of 4° Bé. The waste liquor from this operation is employed for neutralizing the waste acid.

The two layers formed from the acid tar are further worked up as follows:—

(a) Further treatment of aqueous layer. This layer composed of dilute sulphuric acid and alcohols is distilled with superheated steam. A distillate coming over between 80° C. and 150° C. is collected. This water-alcohol distillate is rectified in known manner in a column apparatus. The yield in alcohols (butyl, amyl, hexyl alcohol etc.) amounts to about 2-5% of the acid tar treated and depends, (1) on the composition of the crude benzine—the greater the content of lower boiling constituents (of about 50° C.-60° C.), the higher is the yield in alcohols; (2) on the concentration of the sulphuric acid employed for the refining process and (3) on the refining temperature. The higher the refining temperature and the greater the acid concentration the lower is the yield in alcohol.

(b) Further treatment of the oily layer. The oily layer is neutralized, dehydrated and distilled over lime. Steam is then passed in. The fractions coming over between 50° C. and 200° C. are collected together and form the first fraction (fraction 1), the second fraction (fraction 2) consists of the oils distilling off at between 200° C. and 280° C. When nothing more distils over at this temperature the steam is turned off, the content of the still allowed to cool to about 140° C. and air blown in at this temperature.

Depending on the duration of blowing 100

more or less consistent asphalt-like products are obtained. These products are distinguished by their high elasticity and, unlike the known asphalts, are soluble in benzine and can, therefore, be employed as lacquers.

Fraction 1 is refined with lye and sodium plumbite and again rectified. The product forms a useful insecticide.

Fraction 2 is boiled with a siccative (for example manganese or cobalt siccative) when, according to the temperature, duration of boiling, nature and quantity of siccative, varnish-like products are obtained. 4-5% of manganese siccative is, for example, added to fraction 2 and the mixture boiled for about 24 hours at a temperature of about 180° C.

What we claim is:—

1. A method of producing an insecticide from the waste sludge of cracked mineral oils which comprises mixing the waste acid-containing sludge with water and a weak alkaline solution, allowing the mixture to separate into two layers, removing the upper layer, subjecting the same to steam distillation, thereby producing a plurality of fractions collecting the fractions coming over between 50° C. and 200° C. condensing and combining the fractions to form a condensate and refining the condensate by treating it with lye and sodium plumbite and finally rectifying the refined condensate, thereby producing the insecticide.

2. A method of producing an insecticide from the waste sludge of cracked benzine which comprises mixing the waste acid-containing sludge with water and a waste lye, allowing the mixture to separate into two layers, removing the upper layer, subjecting the same to steam distillation, thereby producing a plurality of fractions, collecting the fractions coming over between 50° C. and 200° C. and condensing to form a condensate, and refining the condensate by treating it with lye and sodium plumbite, and finally rectifying the refined condensate, thereby producing the insecticide.

3. A process for obtaining valuable compounds as insecticides, denaturizing substances, and odorizing agents from waste acids of the mineral oil refining industry, said waste acids having been previously obtained through known processes, the present process consisting in distilling with steam the oily layer formed upon distillation and subsequent neutralization of the acids with water and alkali in the recovery of the acid sludge from the refining of cracked benzine, thereby producing a plurality of fractions coming over between 50° and 280° C., segregating those fractions distilling over between 50° and 200° C. and refining them in the form of a condensate with sodium plumbite, then rectifying the said condensate, and finally combining the rectified condensate with the remaining fractions, coming over between 200° and 280° C., after condensing the latter, to form a final condensate comprising the desired valuable compound.

200° and 280° C. after condensing the latter, to form a final condensate comprising the desired valuable compounds.

4. A process for obtaining valuable compounds as insecticides, denaturizing substances, and odorizing agents from waste acids of the mineral oil refining industry, said waste acids having been previously obtained through known processes, the present process consisting in distilling with steam the oily layer formed upon neutralization of the sludge acids in the recovery of the acid sludge from the refining of benzine, thereby producing a plurality of fractions coming over between 50° and 280° C. segregating those fractions distilling over between 50° and 200° C., and refining them in the form of a condensate with sodium plumbite, then rectifying the said condensate, and finally combining the rectified condensate with the remaining fractions, coming over between 200° and 280° C., after condensing the latter, to form a final condensate comprising the desired valuable compound.

In testimony whereof we affix our signatures.

WACLAW VON PIOTROWSKI.
